UNITED STATES PATENT OFFICE.

EUGENE LANGLEY, OF SAN ANTONIO, TEXAS.

BILGE-WATER DISCHARGER.

1,072,398.

Specification of Letters Patent. Patented Sept. 2, 1913.

Application filed September 16, 1912. Serial No. 720,651.

To all whom it may concern:

Be it known that I, EUGENE LANGLEY, a citizen of the United States, residing at San Antonio, in the county of Bexar and State 5 of Texas, have invented certain new and useful Improvements in Bilge-Water Dischargers, of which the following is a specification, reference being had therein to the accompanying drawing.

10 This invention relates to navigation and has special reference to a device for automatically discharging the bilge water from a boat.

15 The invention more particularly has reference to a device which automatically operates, when the boat is under way, as a suction device to draw off bilge water, while, when the vessel slows so that the pressure on the outside exceeds the suction, the discharge will be automatically closed.

20 The principal object of the invention is to improve and simplify the general construction of devices of this character.

25 Another object of the invention is the production of a device which may be used in small boats with a portable suction nozzle so that the compartments between the different ribs may be thoroughly emptied.

30 With the above and other objects in view, this invention consists in general of certain novel constructions, combinations and arrangements of parts, as will be hereinafter fully described, illustrated in the accompanying drawings, and specifically claimed.

35 In the accompanying drawings, like characters of reference indicate like parts in the several views, and Figure 1 shows a ship equipped with a series of these devices, there being one for each of the water tight compartments.

40 Fig. 2 is an enlarged detail view partly in longitudinal section through a device constructed in accordance with this invention. Fig. 3 is an enlarged detail view of the automatic valve mechanism of such a device. Fig. 4 is a section on line 4-4 of Fig. 3. Fig. 5 is a section on line 5-5 of Fig. 3. Fig. 6 is an enlarged section on line 6-6 of Fig. 2. Fig. 7 is an enlarged detail view of the stop plate. Fig. 8 is an enlarged detail 45 of that portion of the rod wherewith the stop plate engages. Fig. 9 is an end view of the suction funnel blank. Fig. 10 is a side view of the suction funnel.

45 This invention may be considered as consisting of three parts, indicated respectively at A which is the suction funnel, B which

is an automatic valve arrangement, and C which is the delivery funnel. The hull of the boat is indicated at D, and the separate parts of the invention will be now 50 taken up in order.

The suction funnel A has its body made from a blank of sheet metal of a substantially triangular form which is provided with a fold line 10 so that the device 55 is divided in two triangular portions, the corners of these portions being cut away as at 11. This blank is then folded upon itself and so formed as to make a flat, funnel shaped body 12 having bulged sides as can 60 clearly be seen by referring to Fig. 2. In top of the body thus formed is soldered a bushing 13 which is connected by a nipple 14 with an elbow 15, which is also connected by a nipple 16 with a pipe connection 17 wherefrom leads a flexible pipe 18 provided on its opposite end with a pipe 65 connection 19 secured to a nipple 20 which leads to an elbow 21 wherefrom is a nipple 22 which is screwed into a bushing 23 fitted in the upper end of a valve casing 24 of cylindrical form. Into this valve 70 casing is furthermore screwed a ring 25, and a nozzle 26 is held to this ring as shown in Fig. 3. At the lower end of 75 the valve casing is a bushing 27 above which is a ring 28 similar to the ring 25, and these rings are provided with aligned openings to receive the ends of the rods 29 and 30 which are arranged in 80 oppositely disposed pairs. Intermediate their ends, the rods 30 are provided with notches 31 wherein fit the jaws 32 of the stop plate 33 provided with a centrally disposed opening 34. Slidably mounted on the rods 29 85 is a grooved, hollow, ball valve 35 which has movement between the mouth of the nozzle 26 and stop plate 33. Extending from the bushing 27 is a nipple 35' which leads to an ordinary globe valve 36 provided 90 with the usual operating element 37. From this globe valve extends a nipple 28 which is screwed into a plate 39 between which and the bottom of the boat is a washer 40. This nipple extends through the bottom of 95 the boat, and on its lower end is a washer 41 having a V-shaped groove on its upper surface to provide sharp edges to cut into the boat whereby it may be forced tightly 100 against the nipple to prevent leakage. The lower end of this nipple extends through the 105 top wall of a semi-conical casing 42, and is

provided with a nut 43 to jam the casing tightly against the washer 41 and also force the parts firmly in position against the bottom of the boat. This delivery nozzle 42 is secured to the bottom of the boat by means of bolts 44, and is provided with a partition 45 extending from its mouth to a point adjacent the washer 41. On each side of the funnel or delivery nozzle is a skag 46 to protect the funnel from damage.

In the operation of the device, if the globe valve be open and the vessel under speed, suction will be created by the rush of the water past the wider end of the delivery nozzle and this will cause suction in the pipe 18 and consequently suction in the intake or suction nozzle 12. Now, if there be any water in the bilge, the water will be sucked through the pipe past the ball valve and out of the bilge. If for any reason the pressure of the water on the outside exceeds the suction, the ball valve will rise and close the nozzle 26 thus preventing the inflow of water. As this operates automatically no danger of flooding the compartment or the hull of the vessel is experienced. In case of a collision opening the hull of the vessel such as is shown in Fig. 1, the device will operate automatically to clear the compartment of water as long as the vessel continues under steam. There has thus been provided a simple and efficient device of the kind described, and for the purpose specified.

Having thus described the invention, what is claimed as new, is:—

1. In a device of the kind described, a check valve consisting of a cylindrical casing having a bushing at each end, rings within said casing bearing against said bushing, a nozzle carried by the upper ring, pairs of rods connecting said rings, a stop plate fixedly mounted on two of said rods, and a ball valve normally resting on the stop plate.
2. In a device of the kind described, a check valve consisting of a cylindrical casing having a bushing at each end, rings within said casing bearing against said bushing, a nozzle carried by the upper ring, pairs of rods connecting said rings, a stop plate fixedly mounted on two of said rods, a

ball valve normally resting on the stop plate, said stop plate being provided with a centrally disposed opening whereby water may strike the under surface of the ball and close 55 the valve.

3. In a device of the kind described, the combination with a boat hull, of an outlet pipe leading therethrough, a plate on said outlet pipe within the hull, a washer between said plate and hull, a washer on the outside of said hull provided with an annular groove arranged to form a sharp outer edge, a delivery nozzle through one wall of which said pipe passes, and a nut within 65 said nozzle to force the nozzle against the last mentioned washer and pull said plate and washers toward each other.

4. In a device of the kind described, an intake nozzle, a pipe connected therewith, a check valve connected with the pipe, a globe valve connected with said check valve in combination with a boat hull, a pipe leading through said boat hull, a semi-conical nozzle carried on the exterior of said boat hull and 75 into which the last mentioned pipe leads, and skags extending from a point forward of said nozzle to a point aft thereof.

5. In a device of the character described, a check valve comprising a casing, a bushing 80 at each end of said casing, rings mounted in said casing and fitting against said bushings, a nozzle in one end portion of said casing passing through an opening formed in one of said rings and having its end portion 85 formed into a flange clamped between the ring and bushing, rods connecting said rings and holding said rings in engagement with said bushings, a supporting plate mounted in said casing beneath said nozzle and rigidly secured to certain of said rods, and a float mounted in said casing between said nozzle and plate and normally resting upon said plate and slidably connected with certain of said rods whereby said float may be 90 guided into engagement with said nozzle.

In testimony whereof I hereunto affix my signature in presence of two witnesses.

EUGENE LANGLEY.
